UNITED STATES PATENT OFFICE.

WILLIAM R. WRIGHT, OF LA GRANGE, ASSIGNOR OF ONE-HALF TO ROSCOE B. WHEELER, OF DETROIT, MICHIGAN.

DEVICE FOR OILING WINDMILLS.

SPECIFICATION forming part of Letters Patent No. 446,401, dated February 10, 1891.

Application filed October 30, 1889. Serial No. 328,728. (No model.)

To all whom it may concern:

Be it known that I, WILLIAM R. WRIGHT, a citizen of the United States, residing at La Grange, in the county of Cass and State of Michigan, have invented certain new and useful Improvements in Devices for Oiling Windmills; and I do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to an automatic device for oiling windmills; and it consists of an oil-containing vessel or tank supported above the operating mechanism of the mill and provided with pipes or tubing connecting its various oil-discharge ports with the journal-bearings of the mill, and a further arrangement of parts whereby by the swinging of the vane of the mill a lever is operated that raises a valve in the oil-containing vessel and discharges the oil into the pipes or tubing that convey the oil to the several bearings of the mill, all of which will be hereinafter more fully set forth, and the essential features of the device pointed out particularly in the claims.

In the accompanying drawings, forming a part of this specification, Figure 1 is a perspective view of an ordinary windmill, showing my improved oiler mounted thereon. Fig. 2 is a plan view of Fig. 1, a part of the wheel being broken away, showing the vane swung around at right angles to the drive-shaft in position to operate the lever that discharges the oil from the vessel to supply the various bearings of the mill. Fig. 3 is an enlarged central vertical section through the oil-containing vessel or tank. Fig. 4 is a side elevation of same. Fig. 5 is a horizontal section on dotted line xx of Fig. 4. Fig. 6 is an inverted plan of the conical base or platform of the vessel.

As indicated in the drawings, B represents the frame-work of a windmill-tower, and E the top platform thereof. W represents the wheel of the mill, S the drive-shaft, G the crank-

rod, and F the vane, all of said parts being such as are in common use.

A represents the oil-supply vessel, which is supported above the mechanism of the mill in the annular ring z' , mounted on the upright brackets $z z$, that are secured to the turn-table of the mill and revolve therewith, as clearly shown in Fig. 1. Said vessel is provided near its lower end with the bottom D, having the discharge-port e , as shown in Figs. 3 and 5. Located below the bottom D is a conical platform C, the apex c of which being directly under the discharge-port e in the bottom D of the vessel. (See Fig. 3.) At the base of the cone C is a series of holes a , provided with a short tube a' , leading downward therefrom, as shown in Figs. 3 and 6. $a'' a''$ and i are pipes leading from the lower end of the tubes a' to the oil-holes in the journal-bearings of the mill. (See Fig. 1.) The pipes a'' are lead pipes to allow bending so as to couple the parts.

f is a valve-stem passing vertically through the top of the vessel A, and is provided at its lower end with the valve v , said valve being adapted to close the discharge-port e in the bottom of the vessel.

d and d' are braces that cross the diameter of the vessel at right angles to each other, and are secured at their ends to the inner face thereof. (See Figs. 3 and 5.) The lower end of the valve-stem f passes through the braces $d d'$ and is supported therein. To the under face of the brace d is secured the annular case h' , confining the coiled spring s . Said spring environs the valve-stem and is compressed between the valve v and the under face of the brace d , the action of the spring being to hold the valve tightly over the discharge-port e in the bottom D of the vessel, and when the valve has been raised to return it to the closed position, as shown in Fig. 3. The actuating-lever t is fulcrumed in the bracket b , secured to the top of the vessel, and is coupled to the upper end of the valve-stem, as shown in Figs. 1, 2, 3, and 4.

Secured to the arm T of the vane F is the angle-arm k , which, by the swinging of the vane, is adapted to engage with and operate the lever t of the vessel A. The rope or wire 100

5 *r* is secured to the vane, and passes over the pulley *n* down through the sleeve *H*, and its lower end terminates at some point within the reach of the operator. By a downward pull on said rope the vane will swing around to the position shown in Fig. 2, the arm of the vane resting against the rubber buffer *c''*, located in the lug *c'* of the rim of the turn-table of the mill, whereby the angle-arm *k* is held from continually bearing against the actuating-lever *t* of the oil-supply vessel, in which position the mill is out of gear, the wheel standing with its edge to the wind. The means for swinging the vane is in common use.

15 The operation of the device is as follows: The mill being in the position as shown in Fig. 2, and it is desired to oil its several bearings before starting it, a quick downward pull 20 is exerted on the rope *r*, whereby the rubber *c''* is compressed and the vane swung to the position shown by dotted lines in Fig. 2, which carries the arm *k* against the lever *t*, forcing said lever down, as shown by dotted lines in 25 Fig. 3, thus actuating the valve-stem and raising the valve *v*, when the oil will flow through the discharge-port *e* of the bottom *D*, and, dropping directly on the apex *c* of the cone *C*, said oil is divided thereon and flows 30 down the inclined face of the cone in equal quantities in all directions. On reaching the holes in the base of the cone the oil flows into the tubes *a'* therein, and is conveyed through the pipes *a'' a''* and *i* to the various bearings 35 of the mill. When the rope is relaxed, the rubber buffer *c''* will swing the vane slightly out, carrying the arm *k* away from the lever *t*, releasing the pressure thereon, when the spring *s* will force the valve down and close 40 the discharge-port *e* in the bottom *D*, thus stopping the flow of oil.

45 By the employment of the conical base or platform *C* it will be seen that a number of bearings may be oiled simultaneously from one general supply, and that by increasing or decreasing the size of the hole in the base of the cone from which a certain journal receives its supply of oil said journal may be oiled according to its need. It will also be apparent 50 that a separate rope may be employed to operate the lever *t*, which will pass up through the mill-tower and attach directly to said lever. By this arrangement the mill may be oiled without operating the vane for that purpose, as before described, thus keeping the mill in continuous operation, if desired.

55 In Fig. 1 the pipe *i*, that conveys the oil to the head *h* of the crank-rod *G*, is flexible to allow of the rotary motion of said head. Any 60 suitable material may be employed for this pipe; but rawhide is preferred, as it is cheap and very flexible and is preserved by the oil it absorbs, which prevents it from rotting and renders it very serviceable.

65 The brackets *t' t'* on the sides of the supply-vessel *A* serve as stops that engage with the ring *z'* of the brackets *z z* and support

said vessel at the proper height thereon, as shown in Fig. 1.

70 It is designed that the supply-vessel shall contain sufficient oil to freely oil the mill for six months without refilling, and where the device is used in a cold climate a composition of oil will be used for the winter months that will not freeze and that will flow freely even 75 in very cold weather. By the employment of my device the oil may be supplied to the bearings of the mill by the operator standing upon the ground, and the tower need not be mounted but twice a year, and only then to refill 80 the supply vessel or tank.

Having thus fully set forth my invention, what I claim as new, and desire to secure by Letters Patent, is—

1. In combination with the turn-table and 85 vane of a windmill, an oil-supply vessel mounted on the turn-table, a discharge-port in said vessel, a valve to close said port, a stem leading from said valve, an operating-lever coupled to said stem, a supply-pipe leading 90 from the discharge-port of the tank, and an arm mounted on the vane of the mill, whereby the swinging of the vane will actuate the valve of the supply-tank, substantially as and for the purposes specified.

95 2. In combination with the turn-table and vane of a windmill, an oil-supply tank mounted on said turn-table and adapted to turn therewith, a discharge-port in said tank, a series of tubes communicating with the discharge 100 of the supply-tank, a valve to close the discharge of the tank, and mechanism, substantially as set forth, to operate the valve by the action of the vane.

105 3. In combination with the turn-table and drive-shaft of a windmill, an oil-supply tank attached to the turn-table and adapted to turn therewith, a discharge-port in the bottom of said tank, a flexible pipe communicating with the discharge of the tank and 110 adapted to be coupled to the crank-coupling of the drive-shaft, a valve to close the discharge of the supply-tank, and mechanism to operate the valve leading therefrom to a point below the turn-table of the mill, substantially 115 as specified.

120 4. In combination with the turn-table of a windmill and the vane thereof, an oil-supply tank attached to the turn-table thereof, a discharge-port in the tank, an inclined platform located below the discharge-port to receive the oil, a series of tubes leading from said incline, a valve to close the discharge-port of the tank, a stem attached to the valve and passing out of the tank, a spring to close 125 the valve, a lever coupled to the stem, the opposite end of said lever adapted to engage with the vane of the mill, as and for the purposes set forth.

130 5. An oiling device consisting of a supply-tank having in the center of its bottom a discharge-port, a conical platform located below the discharge-port, its apex being located vertically below the discharge of the tank,

there being a series of openings in the base of the conical platform, tubes leading from said openings, a valve over the discharge-port, a valve-rod, and an operating-lever 5 coupled to the valve-rod, substantially as specified.

6. In combination with the tank having a discharge-port, a valve to close said port, a stem passing from said valve out of the tank, 10 an operating-lever coupled to said stem, an inclined platform located below the discharge-

port, said platform having a series of openings through its lower plane, and a series of tubes communicating with said openings, as and for the purposes specified.

In testimony whereof I affix my signature in presence of two witnesses.
